UNITED STATES PATENT OFFICE.

JAY TAMASSY, OF NEW YORK, N. Y., ASSIGNOR, BY MESNE ASSIGNMENTS, TO MILLIE PATENT HOLDING CO. INC., OF NEW YORK, N. Y., A CORPORATION OF NEW YORK.

BAG-TURNING MACHINE.

Application filed August 14, 1922. Serial No. 581,828.

To all whom it may concern:

Be it known that I, JAY TAMASSY, a citizen of Hungary, and resident of the city of New York, in the county of New York 5 and State of New York, have invented certain new and useful Improvements in Bag-Turning Machines, of which the following is a specification.

The present invention relates to improvements in bag-turning machines, and has for its main object to provide a device of this type which is entirely automatic in its operation, the only manual work needed being to place the bags upon supporting members 15 or arms, which carry the bags, one after another, within the reach of the turning mechanism.

Another object of the invention is to produce a bag-turning machine, the turning member of which serves at the same time as a bag filling device.

With these and other objects in view, which will more fully appear as the nature of the invention is better understood, the 25 same consists in the combination, arrangement and construction of parts hereinafter described, pointed out in the appended claims and illustrated in the accompanying drawings, it being understood that many 30 changes may be made in the size and proportion of the several parts and details of construction within the scope of the appended claims, without departing from the spirit or sacrificing any of the advantages 35 of the invention.

One of the many possible embodiments of the invention is illustrated in the accompanying drawings, in which:

Figure 1 is a plan view of a bag-turning 40 machine constructed in accordance with the present invention; Fig. 2 is a central vertical section taken therethrough; Fig. 3 is a front elevation of one of the bag supports, on a larger scale; Fig. 4 is a section taken on line 45 4-4 of Fig. 3; Fig. 5 is a front elevation of a bag support with a bag in position thereon; Fig. 6 is a front elevation of a bag support and the turning element disposed in operative relation thereto; and Fig. 7 is a 50 section taken on line 7-7 of Fig. 6.

The machine comprises a frame, including a base plate 10, from which rise standards 11, the latter supporting a horizontally extending frame member 12, that is spaced 55 from the base 10. In the frame member 12

and in the base 10 is journaled a vertically extending shaft 13, to which intermittent movement is imparted from any suitable source of power. For this purpose, for instance, there is keyed or otherwise attached 60 to the said shaft a sprocket wheel 14, over which runs a chain, not shown, driven by a sprocket wheel on an intermittently moving driving member. To the shaft is fixed, so as to rotate therewith, a drum 15, provided 65 with equi-distantly spaced notches 16, with which co-operates a pawl 17, which is pivoted at 18 to the frame member 12, said pawl serving to prevent overrunning of the drum, or in other words to stop the drum 70 in proper relation to the bag turning mechanism, hereinafter to be described. The pawl is provided with an arm 19, to which is pivoted one end of an actuating rod 20, operated by any suitable mechanism, not shown, 75 which is so timed in relation to the means for intermittently moving the shaft that the pawl is disengaged from a notch in the drum immediately before the shaft is given a partial turn, and is permitted to engage the 80 drum, so as to drop into the next notch in the series, at the end of the partial turn given to the shaft. Obviously any other suitable means may be provided for this purpose, the one herein described having 85 been disclosed for the purpose of illustration only.

On the drum is mounted a plurality of bag supports, said supports being equi-distantly spaced and their number corresponding, obviously, to the number of notches in the drum. Each bag support comprises a pair of spaced arms 21 and 22, mounted upon a block 23, which is provided with trunnions 24, extending horizontally and 90 being journaled in the drum. The arms 21 and 22 are alike in shape, they being of substantially U-shaped transverse cross-section, the arm 21 being fixed by screws 25, or otherwise, to the respective block 23, it extending at right angles to the trunnions 24, while the arm 22 is pivoted at 26 to the block 23, the pivot pin extending also at right angles to the said trunnions, (Fig. 4). The pair of arms, forming a bag support, 95 are spaced apart, their open sides facing one another, as clearly shown in the several figures of the drawings. On each block is mounted a pin 27, carrying an anti-friction roller 28, which co-operates with a station- 100 110

ary cam 29 within the drum 15. The bag supports have a tendency to swing around their trunnions into substantially horizontal positions, (Fig. 2). The cam 29, in co-
5 operation with the pins on the blocks 23, shifts the bag supports into vertical positions before they arrive in operative relation to the bag turning mechanism.

Each of the arms 22 is so designed that it
10 has a tendency to swing toward the respective arm 21 of a bag support, to facilitate the slipping of a bag over the arms. Each arm 22 has mounted thereon a finger 30, which is adapted to co-operate with a sta-
15 tionary cam 31, the latter being so shaped that the arms 22 are caused to swing around their pivots into parallel relation to the respective arms 21 before a bag support arrives into operative relation to the bag
20 turning mechanism.

The bag turning member comprises a vertically extending tube 32, that is reciprocably mounted upon vertical guide rods 33, the latter being carried by a frame member 34, which is mounted upon the frame member 12. The transverse cross-section of the tube 32 is such that it fits the arms of a bag support, when the latter are in their vertical positions and extend in parallel relation to one another. A suitable mechanism 34 is provided for reciprocating the tube 32 in relation to the drum 15, it comprising in the case illustrated in the drawings a lug 35 on the tube 32, said lug being connected by a link 36 with a bar 37. This bar is fixed to a spindle 38, which is oscillatably mounted in a bearing 39, rising from the frame member 12. With the spindle is connected a crank 40, the crank pin 41 of which is engaged by an actuating rod 42, receiving reciprocating motion from any suitable mechanism. The last-mentioned mechanism is so timed, that the tube 32 is caused to move on its downward stroke when a bag support
45 with a bag thereon is brought into alignment with the said tube, the latter moving upwards and being disengaged from the said bag support before the drum 15 is set into motion, to bring the next bag support
50 in the series into alignment with the said tube.

The operation of this machine is as follows: The drum rotates in the direction of the arrow shown in Fig. 1 of the drawings, the bag supports swinging around the trunnions 24 into the positions shown in Fig. 2 of the drawings when the pins 27 thereof are disengaged from the cam 29, and the arms 22 swinging around their pivot pins
55 26 toward the respective arms 21 when the fingers 30 thereof are disengaged from the cam 31. When the elements are in the positions mentioned, the operator slips a bag on each bag support, this operation being
60 65 facilitated by reason of the fact that the

outer ends of the arms are in the positions mentioned nearer one to the other than the width of the mouth of a bag. The bags are then carried one after the other, step by step, into alignment with the tubular turning member 32. While the bag supports, with the bags thereon, move toward the said tubular member, the pivoted arms 22 of the bag supports are swung away from the respective arms 21, thereby distending the mouths of the bags. The supports are also swung around their trunnions 24, arriving thus into alignment with the tubular member 32 in vertical positions. The bottom of a bag on each support is positioned uppermost, it being disposed above the arms of the support, as shown in Fig. 5 of the drawings. When a bag is in alignment with the tubular member, the latter is caused to move on its downward stroke, the tube co-operating with the arms of the support, engaging the bag and turning the same, the bag, while being turned and at the end of the turning operation, being disposed between the tube 32 and the inner faces of the arms 21 and 22, as clearly shown in Figs. 6 and 7 of the drawings. Simultaneously with the turning operation a measured quantity of material may be fed through the tubular member 32 into the bag. Obviously the filling of the bag may be accomplished after the turning operation, just as well.

The connection between the spindle 38 and the crank 40 is, preferably, made by a spring 43, the latter engaging a lug 44 on the crank and a pin 45 on the spindle. The purpose of this arrangement is to permit yielding of the elements, in case a support is not brought into full registry with the tube 32.

What I claim is:—

1. A bag turning machine, comprising a bag supporting mechanism including two spaced arms over which a bag may be slipped, and a tubular turning and filling member reciprocably mounted in relation to and between said arms engaging a positioned bag and reversing the same while advancing toward and between said arms.

2. A bag turning machine comprising a bag supporting mechanism including two spaced parallel arms over which a bag may be slipped, and a tubular turning and filling member reciprocably mounted in relation to and between said arms engaging a positioned bag and reversing the same while advancing toward and between said arms.

3. A bag turning machine comprising a bag supporting mechanism including two spaced arms over which a bag may be slipped, each of said arms having a substantially U-shaped transverse cross-section and their open sides facing one another, a tubular turning and filling member reciprocably mounted in relation to and between said

- arms engaging the positioned bag and reversing the same while advancing toward and between said arms.
4. A bag turning machine comprising a bag supporting mechanism including two spaced parallel arms over which a bag may be slipped, each of said arms having a substantially U-shaped transverse cross-section and their open sides facing one another, a tubular turning and filling member reciprocably mounted in relation to and between said arms engaging the positioned bag and reversing the same while advancing toward and between said arms.
5. A bag turning machine, comprising a bag supporting mechanism including two spaced arms over which a bag may be slipped, one of said arms being fixed and the other one pivoted, means for causing the free end of the pivoted arm to swing toward said fixed arm to facilitate the positioning of a bag on said arms, means for swinging said pivoted arm away from said fixed arm, thereby distending the bag thereon, and a tubular turning and filling member reciprocably mounted in relation to and between said arms engaging the positioned bag and reversing the same while advancing toward and between said arms.
6. A bag turning machine comprising a conveyer, a plurality of bag supporting frames mounted on said conveyer, each supporting frame comprising two spaced arms over which a bag may be slipped, one of said arms being fixed and the other one pivoted, means for causing the free end of the pivoted arm of each set to swing toward the respective fixed arm to facilitate the positioning of a bag on said arms, means for swinging said pivoted arms away from the respective fixed arms, thereby distending the bags thereon, a tubular filling and turning member, means for causing intermittent motion of said conveyer so as to bring said bag supporting members step by step into alignment with said tubular member, and means for causing said tubular member to move into and out of a bag support during each interval of rest of said conveyer.

Signed at New York, in the county of New York, and State of New York, this 20th day of July, A. D. 1922.

JAY TAMASSY.
